A. Leonard's Design for Tea and Coffee Pots
Assigned to Rogers Brothers Manufacturing Co

Patented Feb. 23, 1858.

No 991.

LEONARD

Des. 991

A. Allen Leonard, of Hartford, Conn.
Assignor to
Rogers Brothers, Manufacturing Company, of same place.
Letters Patent No. 991, Dated Feb. 23rd 1858.

The schedule referred to in these Letters Patent & making part of the same.

To all whom it may concern:

Be it known that A. Allen Leonard, of Hartford, in the county of Hartford, and state of Connecticut, have invented a new Design for Tea and Coffee Pots: & I do hereby declare that the following is a full, clear, and exact description of the same: reference being had to the accompanying drawings making part of this specification, which drawing represents a side view of a Coffee Pot, of my design.

This design embraces the shape of the body, the ornamental rims, the feet, the handle, the spout, and the tip of the pot, all of which are fully represented in the drawing. The shape of the body, the configuration of the upper rim, the feet, the ornaments on the lower rim, between the feet, and the tip, partake of the Louis Quatorze character. The handle and spout are embellished with combinations of floral and leaf scroll ornament. The edge of the upper rim has upon it a series of relief ornaments a. a. and b. b. alternating with each other all round, and under each ornament a. is a floral ornament c. c. in relief. The ornamentation d. e. e. of the feet is such that small ornaments f. f. interposed between the upper parts of them, complete a continuous line of relief ornament all round the rim. The handle has a similar flower g. on each side and the remainder of its ornamentation is made up of leaf scroll work, all in relief, as is indicated by h. i. j. k. both sides being exactly alike. The spout has on each side a similar cluster of flowers l. m. n. and leaves o. o. and the remainder of its ornament is made up of leaf scroll work p. q. r.

2

Dec. 991

The ornament of the tip is the same on both sides, as is indicated by S. T. in the drawing. The shape of the body can be better understood by reference to the drawing than by any description. What I claim as my invention, and desire to secure by Letters Patent, is: —

The shape of the body and the configuration and ornamentation of the upper and lower rims, the feet, the handle, the spout, and the tip, combined, as herein described & represented in the drawing, to produce an ornamental design for a tea or coffee pot.

Witnesses.
